UNITED STATES PATENT OFFICE.

ALPH JORDAN WILSON, OF CHICAGO, ILLINOIS.

LEAF FOR LOOSE-LEAF LEDGERS.

1,143,155.

Specification of Letters Patent. Patented June 15, 1915.

Application filed November 19, 1914. Serial No. 872,900.

To all whom it may concern:

Be it known that I, RALPH J. WILSON, a citizen of the United States, and a resident of Chicago, in the county of Cook and State of Illinois, have invented certain new and useful Improvements in Leaves for Loose-Leaf Ledgers; and I do hereby declare that the following is a full, clear, and exact description thereof, reference being had to the accompanying drawings, and to the characters of reference marked thereon, which form a part of this specification.

This invention relates to improvements in loose leaf ledgers, and refers more specifically to a novel supplemental sheet for such ledgers adapted to be interleaved with the regular pages of the ledger to segregate a given class of accounts from the body of the accounts to permit ready reference to the segregated accounts, said supplemental leaves being also adapted to receive thereon memoranda relating to the history and character of the account with which it is associated and contained in the adjacent page, so that by comparing the account with its historical data any person having access to the ledger, whether he is familiar with the account or not, will at once know the character of the account and the manner in which it is to be treated for collections or otherwise.

As a means for segregating accounts of a given class, the supplemental leaves are fastened in the ledger by means which permit them to be shifted in their planes so that in one position portions of them are exhibited beyond the margins of the main leaves, and in another position they are concealed between the main leaves; the exhibited portion of the supplemental leaf constituting means to segregate the associated account and to enable the same to be readily located for inspection.

A specific use for which my invention has been adapted is to readily locate delinquent accounts in a ledger, and to provide means whereby a history of the account may be kept in compact form, and in such relation to the account as to be readily compared thereto, and also to provide means whereby the particular manner for collecting the account may be noted, so that persons having to do with the account, such as the book-keeper, collector, salesman, or credit man, may have at hand for ready reference a complete and concise history of the account and

the manner in which the collections thereon are intended to be handled.

It is a feature of my invention that the supplemental leaf is attached to the ledger between the main leaves in such a way that while occupying one position it is contained wholly between the main leaves and is thereby concealed, and when occupying another position it projects from the main leaves at one margin of the ledger so to indicate the location of the associated account. This result may be effected in a practical manner by providing the attaching margin of the supplemental leaf with two sets of perforations to engage over the binding posts of the ledger, one set being slightly below the other. In practice it is desirable to expose but a small portion of the supplemental leaf as, for instance, a relatively small tab at one edge thereof. When an account becomes delinquent, or for other reason it is desirable to quickly locate an account of a certain class, the supplemental leaf is detached from the posts, shifted upwardly and reattached thereto in a position in which the tab or other portion is exhibited beyond the margins of the main leaves. When the account changes its character so as not to require special attention the leaf is again detached and attached to the posts in a position in which the same is concealed within the ledger.

I have shown in the drawings one form of my improved ledger leaf as applied to the ordinary loose leaf ledger.

As therein shown:—Figure 1 is a plan view of an open ledger showing my novel supplemental leaf in position to exhibit a portion thereof beyond the margins of the main leaves of the ledger. Fig. 2 is a similar view showing a supplemental leaf in its concealed position. Fig. 3 is a plan view, on an enlarged scale, showing the supplemental leaf in its concealed position and illustrating the manner of attaching it to the binding posts of the ledger.

As shown in the drawings, 10 designates, as a whole, the supplemental ledger leaf referred to. It is provided at its attaching margin with two sets of perforations 11, 12, respectively, adapted to fit over the binding posts 14 of the ledger by which the main leaves 15 thereof are held in place. The said supplemental leaf is made narrower than the main leaves 15. It is ruled on one

2
or both sides to receive data relating to the account with which it is associated. As herein shown, it is ruled to provide at its top a space 16 to receive the name of the 5 account. Below said space and near the left hand margin of the leaf, it is ruled to provide a space 17 to indicate in what manner the account is to be collected. Below the heading of the space "How to collect" are 10 printed indicia, such as "Salesman," "Collector," "Phone," "Letters," "Draft" to indicate in what manner the account is to be collected. At the right hand side of said space 17 is provided a vertical column 18 in 15 which a check mark is indorsed opposite to the particular designation indicating the manner in which the account is to be collected. For instance, if the account is to be collected by the salesman, a check mark is 20 placed in the column 18 after the word "Salesman," and if the account is to be collected by the regular collector, a check mark is entered in the column 18 opposite the word "Collector." If the account is to be 25 attended to by telephone, letter or sight draft, a check mark will be placed in column 18 opposite the particular appropriate designation. Below the space 18 is arranged other spaces 19, 20 and 21, the first to receive data with respect to letters written, 30 the second to receive the salesman's report, and the third to receive the collector's report. Above said spaces 20 and 21 is a space 22 which may be devoted to general 35 remarks with respect to the character of the account.

In Figs. 1 and 3 is shown the exhibited position of the supplemental leaf, in which position it is attached by engagement of the 40 perforations 11 with the binding posts 14. In this position the exhibition tab 23 or other part of the leaf to be exhibited is located above the top margins of the main leaves but within the covers 24 of the 45 ledger. When the supplemental leaf is applied to locate delinquent accounts in a ledger each delinquent account has inter-leaved therewith one of the supplemental sheets, and any one having to do with the 50 accounts whether the salesman, collector, book keeper or credit man may, without consulting any one else, readily find or locate all the delinquent accounts and have at hand for ready reference a complete history 55 of the account, the manner in which it is to be collected, etc. With such accounts where such service is required at intervals, the supplemental leaf may be lowered within the

ledger when the account is normal so as not to be exhibited. At the same time the 60 history of the account remains in its proper place for ready inspection, and the leaves may be adjusted when required to exhibit them when the account becomes delinquent.

Preferably, the supplemental leaf is so 65 related to the last page of the account that it lies opposite to the said last page when the book is open, as indicated in Figs. 1 and 2. However, in practice, the supplemental leaves will be ruled on both sides so that, 70 when necessary, the two sides of the leaf may receive data relating to the account.

While I have made specific reference to the use of the supplemental leaf in connection with delinquent accounts, it will be understood that it may be appropriated to other classes of accounts which it may be desirable to periodically segregate from the body of accounts in the ledger.

I claim as my invention:

80 1. A loose leaf ledger provided with leaf attaching posts, and with main leaves having perforations to engage over said posts, combined with a supplemental leaf provided with two sets of perforations for separate engagement with said posts and provided at one margin with a projecting tab.

85 2. A ledger leaf for the purpose set forth provided at its attaching margin with two sets of perforations adapted to separately engage over the ledger leaf attaching posts, and provided at one margin with a projecting tab.

90 3. A supplemental ledger sheet for the purpose set forth provided at its attached margin with two sets of fastening means adapted to separately engage the ledger leaf anchoring means and provided at one margin with a projecting tab, said leaf being further provided near one margin with a 95 space to receive the name of the ledger account to which the leaf is appropriated, with other spaces to severally receive indicia relative to the manner of collecting the account, and with other record spaces 100 severally appropriated to the indicia data to receive from time to time historical data 105 relative to the collection of the account.

110 In testimony, that I claim the foregoing as my invention I affix my signature in the presence of two witnesses, this 17th day of November, A. D. 1914.

RALPH JORDAN WILSON.
